UNITED STATES PATENT OFFICE.

HAROLD G. BAXTER, OF WILKINSBURG, PENNSYLVANIA, ASSIGNOR TO WESTINGHOUSE ELECTRIC AND MANUFACTURING COMPANY, A CORPORATION OF PENNSYLVANIA.

CIRCUIT-INTERRUPTER.

1,246,380.

Specification of Letters Patent. Patented Nov. 13, 1917.

Application filed April 29, 1915. Serial No. 24,752.

To all whom it may concern:

Be it known that I, HAROLD GODFREY BAXTER, a subject of the King of Great Britain, and a resident of Wilkinsburg, in the county 5 of Allegheny and State of Pennsylvania, have invented a new and useful Improvement in Circuit-Interrupters, of which the following is a specification.

My invention relates to circuit interrupters and particularly to contact members for the same.

The object of my invention is to provide a contact member for a circuit interrupter that shall have a wiping action when the 15 contact members are moved into and out of engagement with each other.

The single figure of the accompanying drawing is a view, mainly in side elevation but partially in section, of a portion of a 20 circuit interrupter embodying my invention.

Main stationary contact members 1 and 2 are mounted on supporting rods 3 and 4, as is usual in circuit breakers of well 25 known construction. A movable bridging member 5 is attached to a rod 6 and has a main movable contact member 7 and auxiliary movable contact members 8 and 9 mounted thereon. Each of the auxiliary 30 movable contact members 8 and 9 is provided with a cylindrical lower portion 10 that is disposed in an opening 11 in the member 5. The opening 11 is cylindrical in shape and its upper portion 12 is of enlarged diameter to receive a helical supporting spring 13, one end of which rests 35 upon an annular shoulder 12a that constitutes the bottom of the space 12 and the other end of which engages the under side 40 of the main portion of the one or the other of the movable contact members 8 and 9. Each cylindrical portion 10 is provided with a diagonal groove 14 to receive the end of a guiding pin 15 with which the member 5 45 is provided. The groove 14 and the pin 15 are so disposed that, when the auxiliary movable contact members 8 and 9 are elec- 50 trically connected together by a flexible conductor 18.

In the position shown in the accompanying drawing the contact members 8 and 16 55 and the contact members 9 and 17 are in en-

gagement, and the springs 13 are compressed. If it is desired to open the circuit interrupter, the rod 6 is moved downwardly to disengage the main contact member 7 from the main stationary contact members 1 and 2. The movable contact members 8 and 9 remain in engagement with their co-operating auxiliary stationary contact members 16 and 17, respectively, until the springs 13 have reached their limit of expansion. However, while the springs are 60 expanding, the movable contact members 8 and 9 are turning so as to secure a wiping action with respect to the stationary contact members 16 and 17. 65

If it is desired to close the circuit interrupter, the rod 6 is moved upwardly until the auxiliary contact members 8 and 9 engage the stationary contact members 16 and 17, respectively, and the springs 13 are compressed. While the springs 13 are being 70 compressed, the contact members 8 and 9 are being turned to secure good electrical contact and to clean the surfaces of any irregularities or pits that may be caused by the 75 arcing incident to opening the circuit. After the auxiliary contact members are engaged, the main contact member 7 engages the stationary main contact members 1 and 2. 80

While I have shown my invention in its preferred form, it will be understood that various modifications may be made therein without departing from the spirit and scope 85 of the invention as set forth in the appended claims.

I claim as my invention:

1. A circuit interrupter comprising a stationary contact member, a movable member, a movable contact member mounted on the 90 movable member, and means dependent only upon the relative movement of the movable members for causing the movable contact member to turn in a plane parallel to the contact surface of the stationary contact member when the contact members are engaged. 95

2. A circuit interrupter comprising a stationary contact member, a movable member, a movable contact member mounted on the 100 movable member, and means depending upon the relative movement between the movable member and the movable contact member for causing the movable contact member to turn in a plane parallel to the 105

contact surface of the stationary contact member.

3. A circuit interrupter comprising a stationary contact member, a movable contact member, a movable supporting member for the movable contact member, said movable contact member being adapted to be relatively movable with respect to its supporting member, and means dependent only upon the relative movement of the movable members for turning the movable contact member in a plane parallel to the contact surface of the stationary contact member.

4. A circuit interrupter comprising a stationary contact member, a movable member, a movable contact member resiliently mounted on said movable member, and means dependent only upon the relative movement of the movable members for imparting a rotative movement to said movable contact member in a plane parallel to the contact surface of the stationary contact member as it is moved longitudinally.

5. A circuit interrupter comprising a stationary contact member, a movable member having a pin and a movable contact member resiliently mounted on the movable member and having a groove to receive the inner end of said pin for imparting a rotative movement to said movable contact member as it is moved relatively to the movable member.

6. In a circuit interrupter, the combination with a stationary contact member, of a movable member having a pin, a movable contact member disposed in the movable member, and a resilient member for supporting the movable contact member, said movable contact member having a groove which is engaged by the pin in the movable member for effecting a rotative movement of the movable contact member as the resilient

member is compressed and expanded by reason of the engagement and disengagement of the contact members.

7. A circuit interrupter comprising a stationary contact member, a movable supporting member, a movable contact member, means for resiliently supporting the movable contact member on the movable supporting member, and means dependent upon the relative movement between the movable contact member and its supporting member for turning the movable contact member in a plane parallel to the contact surface of the stationary contact member.

8. A circuit interrupter comprising a stationary contact member, a movable supporting member having a projection therein, and a movable contact member resiliently mounted on the supporting member and having a cam surface that is adapted to coöperate with the projection in the supporting member to cause the movable contact member to turn in a plane parallel to the contact surface of the stationary contact member when the movable contact member moves relatively to its supporting member.

9. A circuit interrupter comprising a stationary contact member, a movable supporting member, a movable contact member, a spring for resiliently supporting the movable contact member on the supporting member, said supporting member having a pin therein, said movable contact member having a groove therein to receive the said pin, said pin and groove being adapted to coöperate to turn the movable contact member when the spring is compressed.

In testimony whereof, I have hereunto subscribed my name this 24th day of April 1915.

HAROLD G. BAXTER.
